ABSTRACT: A system for solution mining of minerals with heated solvent includes a single-bore hole provided with a string of pipe having a central conduit, an intermediate annular conduit surrounding the central conduit and an outer annular conduit enclosed by a casing. Prior to production recovery of the mineral, both the outer annular conduit and the intermediate annular conduit may be used for undercutting the mineral cavity if desired by pumping water through both conduits while recovering through the central conduit. The change from the undercutting to the production stage may be accomplished without loss of well pressure by pumping an oil-water-clay composition, herein sometimes referred to as a gel, an oil-water-clay gel, or an oil gel having a density less than that of water into the intermediate conduit without capping its bottom orifice to thereby thermally insulate the central conduit from the outer conduit. In production, heated water is pumped down the outer annulus and the chilled solution is recovered from the central conduit.

METHOD AND APPARATUS FOR SOLUTION MINING

SUMMARY OF THE INVENTION

In mining a potash cavity, a string of pipe is provided including a central conduit, an intermediate annular conduit about the central conduit and an outer annular conduit, all communicating with the potash and the underlying salt beds. The potash bed is undercut by pumping water through two of the conduits to dissolve the underlying salt, and the solution is recovered from the third conduit which may, for example, be the central conduit. A back pressure is maintained on the discharged salt solution at a level sufficient to generate a pressure in the cavity slightly less than the formation pressure. When it is desired to change to the dissolving and production of potash, an insulating oil-water-clay gel is pumped to fill the intermediate annulus without capping the down-hole aperture thereof and while maintaining the system pressure. During production, hot water is pumped through the outer annulus and the cooler solution is recovered through the central conduit. By providing an oil-base gel in the intermediate annular conduit we have found that we provide a very effective insulating barrier between the inner and outer conduits; and this minimizes the transfer of heat from the downcoming hot water and the upcoming solution thereby allowing the introduction of heat into the cavity to replace most of the heat lost by the dissolving of the potash ore.

It has been found that the intermediate annulus filled with an oil-water-clay gel having a thickness of about 1 inch provides an extremely good insulation so that a minimum amount of the heat in the hot water is lost to the solution being recovered. The oil-water-clay gel remains in the intermediate annulus even though the down-hole aperture is not capped because the gel is lighter than water.

The invention, therefore, permits solution mining of potash with a single well-bore while allowing the advantage of having three separate conduits communicating with the mineral cavity which may be used independently, if desired. It has been found that there is very little, if any, deterioration of the insulating properties of the oil-water-clay gel over prolonged periods of use. There is no appreciable settling of particles from the gel even over extended periods of time, during which pressure may, of course be maintained on the well. Further it has been found that there is no substantial displacement of the gel by the water or brine even though the down-hole aperture of the intermediate annulus is not capped. Because the intermediate annulus is not capped, the placement and removal of the drilling casing are greatly facilitated.

The unit insulating properties of the gel against heat conduction have been found to be approximately equal to a microscopically thin oil film which is known to have excellent insulation effect. The gel minimizes convection currents which normally take place in oil films having a thickness greater than microscopic, and it thereby advantageously extends the excellent insulating properties of the oil into thickness ranges in which it would otherwise be ineffective.

Other features and advantages of the present invention will be apparent to persons skilled in the art from the following detailed description of a preferred embodiment accompanied by the attached drawing.

THE DRAWING

The drawing is a vertical view, in cross section, of a solution mining system illustrating the invention.

DETAILED DESCRIPTION

Turning then to the drawing, reference numeral 10 generally designates pipe means including first inner or central tubing 11, an intermediate tube or pipe 12 and an outer casing 13 which may have an exterior coating of cement if desired. The pipe 11 defines a central bore 14. The space between the outer surface of the pipe 11 and the inner surface of the pipe 12 forms an intermediate annular conduit 15. The spacing between the outer surface of the tube 12 and the inner surface

of the casing 13 forms an outer annular conduit 16. The pipe means extends through the earth 18 into a subterranean layer of potash 19 or other mineral to be recovered by solution mining. Typically, a layer of sodium chloride designated by reference numeral 20 exists beneath the potash 19. The potash layer may have a thickness typically in the range of 20-40 feet. The overall depth of the pipe string may be 4,000-5,000 feet or more, and the down-hole aperture 23 of the central conduit 14 is located at a depth of about 10 feet beneath the down-hole aperture 25 and 26 of the intermediate annular conduit 15 and outer annular conduit 16.

Prior to the production stage of recovering the potash, it may be desirable to undercut the potash layer 19 as at 27, and because the intermediate annulus 25 is not capped, water for undercutting the sodium chloride may be pumped both from a main hot water pump 30 connected via pipe 32 to the outer casing 13 for forcing water through the annular conduit 16 and from an auxiliary pump 31 connected to the intermediate

10 tube 12 for supplying water to the annular conduit 15. A pressure valve 34 is interposed in the central conduit 11 to couple the brine to an outlet conduit 33 while maintaining system pressure. Persons skilled in the art will appreciate that it is desirable to continue to maintain system pressure at all times

15 once it has been achieved. The water used for undercutting the potash need not be heated to any significant degree in this case because the heat loss from dissolving the sodium chloride is negligible and, therefore, the temperatures between the incoming water and outgoing brine solution are about the same.

20 However, during the production stage hot water is pumped from the main pump 30 through the outer conduit 16, and a chilled solution containing the dissolved potash is recovered through the central conduit 14 via the pressure valve 34. In this case, there is a considerable difference in temperature between the incoming and outgoing fluids; and it is, of course, highly desirable to maintain this temperature difference so that the hot water can be used to replace most of the heat lost due to the chilling effect of the dissolving of the potash.

25 Hence, during production, we use the auxiliary pump 31 to pump an oil-water-clay gel into the intermediate annular conduit 15 to substantially fill that conduit and thereby thermally insulate the central bore 14 against heat transfer from the outer annular conduit 16.

30 The insulating material in the annular conduit 15 is preferably lighter than water. This has the advantage that the annular opening 25 need not be capped thereby permitting the changing from the undercutting to the production stage without having to reduce system pressure. Secondly, by having

35 the insulating material being a pumpable fluid which is lighter than water and which does not mix with water, the insulating material will not be displaced from the annular insulating conduit 15 during production but may be removed when the mining is terminated. The insulating properties of the system will not deteriorate appreciably with time. However, prior attempts to use a fluid such as ordinary petroleum oils in the insulating annular conduit 15 have proved unsuccessful because of the existence of heat convection currents in that fluid. As already mentioned, the depth to which the pipe means extends

40 may be of the order of 4,000-5,000 feet or even greater beneath the surface of the earth.

45 Because the well is this deep and the mining becomes more expensive as bore size is increased, it is advantageous to utilize insulating materials that are effective in thin layers. We have discovered that we can attain these advantages and achieve yet further advantageous operation by utilizing gels. Persons skilled in the art will appreciate that such gels can be readily removed and replaced without affecting the pressure on the system.

EXAMPLE I

In a preferred embodiment, we mix diesel oil with 2 percent water by volume to which we add a gelling agent containing clay and sold as Geltone A and manufactured by the Baroid

Division of National Lead Company. It will be appreciated that many other petroleum oils may be employed in place of the diesel oil with like results. The agent is added at the rate of about 12.5 pounds of gelling agent per 42 gallons of diesel oil. We thus achieve a stable oil-water-clay composition which is low enough viscosity so that it may easily be pumped into place by the auxiliary pump 31, and yet high enough viscosity to almost completely eliminate convection currents in the insulating fluid. However, a range of about 8 to about 15 pounds of the gelling agent per 42 gallons (i.e. barrel) of oil with about 2-5 percent of water is believed to be effective.

With the oil-water-clay gel sheath having a thickness (that is difference between the outer radius and inner radius) of 0.933 inch, we have been able to achieve an insulation factor, k , of 1.02 B.t.u. per hr. per foot² per inch. This compares with a k of 1.002 B.t.u. per hr. per foot² per inch for a microscopically thin film of diesel oil; and it is well known that such thin oil films have excellent insulating qualities. Thus the invention achieves the advantage of having two separate inlet conduits, if desired, as well as an outlet conduit during undercutting while permitting heat insulation of the centermost conduit from the outermost annular conduit in an annular piping means.

Further, the oil gel has a lesser density than water and/or salt and potash brines and does not mix appreciably with them; and we have found that the gel will stay in place despite not having to cap the down-hole aperture 25 for long periods of time with no breakdown of the gel and without appreciable reduction in the insulating properties of the gel. With this system we are also able to easily recover the tubing and casing which are reusable.

The filling of the annular conduit 15 with the oil gel is accomplished by pumping the oil gel and measuring the volume to displace whatever fluid may be in that conduit.

With the oil gel as described above in the annular conduit 15 and that conduit having a thickness of 0.933 inch, hot water at a temperature of 160° and the depth of the well being about 4,400 feet, we found that the temperature of the water exiting from the annulus 26 was about 150° and that the temperature of the brine into the down-hole central aperture 23 was about 122°. The temperature of the fluid recovered from the pressure valve 30 was about 117° F., showing little heat transfer between the liquids separated by the insulating gel.

Although we have achieved satisfactory results with the above gel, any organophilic clay such as montmorillonite or attapulgite may be used with various petroleum oils such as diesel oil, naphtha, and other distillate oils, and water provided the resultant gel is easily pumpable yet has high enough viscosity to eliminate or substantially reduce heat convection currents in the intermediate conduit.

EXAMPLE II

A gelling reagent may be prepared in the field by exchanging suitable amines or amino salts in the presence of concentrated HCl on to sodium bentonite and using CMC (carboxyethylcellulose) to bridge the molecules. Sodium bentonite is well known as a class of montmorillonite clay which may be reacted by cation exchange to form the gelling agent as follows:

Further thickening may be achieved by adding a small amount of CMC which bridges between the bentonite/amine molecules. Weight ratios of the amine, sodium bentonite and HCl are of the order 10:1:3. Diesel oil with 2-5 percent water by volume is blended into the system after the above reaction until a gel having the desired viscosity and pumpability are achieved (for example about 12 pounds of the gelling agent per barrel of the oil and water).

With the inventive system we achieve the further advantage of having a single-hole mining system which is capable of both undercutting, i.e. dissolving underneath, the potash layer, if 75

desired, and readily converting to the production stage without reducing system pressure. It will be appreciated that two-hole systems are particularly to be avoided where the beds of potash are thin and they dip appreciably.

5 Further, the invention represents a relatively inexpensive method of achieving a very good insulation by using materials which are readily available, easy to prepare and easy to install.

Further, because there is no bottom plug or cap to the intermediate annular conduit, the oil-water-clay gel insulating layer is part of the entire hydraulic system and can easily be removed by pumping displacing liquid down the outer conduit while closing the pressure valve 30 and replacing the auxiliary pump 31 with a similar pressure relief outlet valve.

10 Another advantage of the system is that since the oil gel is part of the closed fluid system, it may be used to record the fluid pressure in the system if this is more convenient than recording in either of the other two conduits.

Having thus described in detail a preferred method of solution mining using a single drill-hole together with apparatus and material for accomplishing the same, persons skilled in the art will be able to modify certain of the steps described and to substitute materials or elements for those which have been disclosed or illustrated; and it is, therefore, intended that all 20 such substitutions and modifications be covered as they are embraced within the spirit and scope of the appended claims.

We claim:

1. In a system for solution mining, the combination comprising piping means including a first tube defining a central conduit, a second tube about said first tube and defining therewith an intermediate annular conduit, and an outer casing about said second tube and defining therewith an outer annular conduit, said central conduit and said intermediate and outer annular conduits communicating directly with a deposit of the mineral to be mined; means for pumping a heated fluid into one of said central conduit and said outer annular conduit; a stable gelled oil-water-clay composition having a density less than the density of water and of pumpable viscosity in said intermediate conduit to fill the same and thermally insulate said central and outer annular conduits from each other.

30 2. The system of claim 1 wherein said composition comprises sodium bentonite mixed with a gelling agent and blended with a mixture of petroleum oil and water, said water being in the range of 2-5 percent of the mixture by volume and said sodium bentonite being in the range of 8-15 pounds per barrel of oil.

35 3. The system of claim 1 wherein the lateral spacing between the inner and outer walls of said intermediate annular conduit is about 1 inch and the thermal conductivity, k , of said composition in use is about 1.02 B.t.u. per hour per square foot per inch of gel.

40 4. The system of claim 1 further comprising pump means for selectively pumping said composition into said intermediate conduit to fill the same; and pressure valve means connected to the other of said central bore and outer annular conduit for releasing brine therefrom while maintaining system back pressure.

45 5. The system of claim 1 characterized in that the down-hole aperture of said intermediate annular conduit remains open.

50 6. In a method of solution mining the steps of placing a pipe string in a well-bore, said string having a central bore, an intermediate annular conduit and an outer annular conduit, all communicating with the cavity of the mineral to be mined, pumping a heated solvent through one of said central bore and outer annulus, recovering the resultant solution through the other of said central bore and outer annulus, and maintaining an insulating oil-water-clay gel in said inner annulus.

65 7. The method of claim 6 wherein said gel comprises sodium bentonite mixed with a gelling agent and blended with a mixture of oil and water, said water being in the range of 2-5 percent of said mixture by volume and said sodium bentonite being in the range of 8-15 pounds per barrel of oil.

8. The method of claim 6 wherein said intermediate annular conduit defines a spacing of about 1 inch between its inner and outer walls.

9. A method of solution mining of a mineral in a cavity located adjacent a body of a salt beneath the surface of the earth comprising installing conduit means in a well-bore communicating with the cavity including a central conduit, an intermediate annular conduit about said central conduit and an outer annular conduit about said intermediate conduit, all communicating said mineral with a surface location, forcing solvent through two of said conduits while recovering dissolved salt from the other conduit to undercut said mineral cavity, then pumping a stable oil-water-clay gel in said intermediate conduit to thermally insulate said central bore from said outer conduit, then pumping a heated solvent into one of said central and outer conduits to dissolve said mineral, and

recovering the resultant solution with dissolved mineral from the other of said conduits.

10. The method of claim 9 wherein said mineral is potash and said gel is an oil-water-clay composition mixed with a 5 gelling agent to provide a pumpable gel which minimizes transfer of heat by conduction between said central and outer conduits.

11. The method of claim 9 wherein said solvent is hot water introduced into a potash cavity via said outer annular conduit 10 and wherein the brine is recovered from said cavity through said central conduit.

12. The method of claim 9 further comprising the step of sealing the recovery conduit and forcing a liquid into the entrance conduit to force said gel out of said intermediate conduit, then recovering the drill tubing.
